ATTORNEY

UNITED STATES PATENT OFFICE.

SIMON TOFFLER, OF NEW YORK, N. Y., ASSIGNOR TO ANNA TOFFLER, OF SAME PLACE.

FLOOR-MAT.

SPECIFICATION forming part of Letters Patent No. 276,983, dated May 1, 1883.

Application filed March 7, 1883. (No model.)

To all whom it may concern:

Be it known that I, SIMON TOFFLER, of the city, county, and State of New York, have invented certain new and useful Improvements 5 in Floor-Mats, of which the following is a specification.

This invention has reference to an improved construction of floor-mats, for cars, halls, and other purposes, of that class which may be readily rolled up or folded together when it is desired to clean the floor; and the invention consists of a number of transverse slats which are connected at two or more points by straps or bands applied to the slats, and by intermediate links passing through sleeves of the straps or bands, said links holding the slats at proper distance from each other.

In the accompanying drawings, Figure 1 represents a plan of my improved floor-mat. Fig. 2 is an enlarged portion of the same, drawn partly in section. Figs. 3 and 4 are vertical transverse sections, respectively, on lines xx and yy , Fig. 2; and Fig. 5 is a detail vertical transverse section on line zz , Fig. 2.

Similar letters of reference indicate corresponding parts.

A A in the drawings represent a number of slats or rods of wood, metal, or other suitable material, and of round, square, or other cross-section. The slats A A are connected at two or more points by means of flat straps $a a$, of sheet metal, which are passed through transverse slits or mortises $b b$ of the slats A, and provided at both ends with sleeves $a' a'$, equal 35 in width with the body of the link. The flat body of the straps $a a$ is held tightly in the slits or mortises $b b$ of the slats A by means of

ferrules d , placed over the ends of the slats, as shown in Fig. 2. When a more ornamental floor-mat is desired, the straps $a a$, instead of being made flat and passed through transverse slits or mortises of the slats, are made in the shape of bands encircling the slats, as shown in Figs. 3 and 4. The encircling bands $a a$ are, like the straps $a a$, provided with sleeves $a' a'$ at both ends. The adjoining sleeves $a' a'$ of the straps or bands $a a$ are again connected by wire links $e e$, which are located parallel to and intermediately between the slats, by which not only the proper distance between the slats, but also a more flexible connection of the same is secured, so that the floor-mat can be rolled up or folded into narrow compass whenever required.

I am aware that slat mattings with flexible connections, which permit the rolling up of the same, have been used heretofore, and I do not broadly claim the same.

Having thus described my invention, I claim as new and desire to secure by Letters Patent—

As an improvement in floor-mats, the combination of transverse slats A A, connected at two or more points by transverse straps or bands $a a$, having sleeves $a' a'$ at both ends, with intermediate links, $e e$, passed through adjoining sleeves of the straps or bands $a a$, substantially as and for the purpose set forth.

In testimony that I claim the foregoing as my invention I have signed my name in presence of two subscribing witnesses.

SIMON TOFFLER.
